CONFECTION

James Babcock, Pomona, Calif.

Application May 31, 1955, Serial No. 36,282

Term of patent 14 years

(Cl. D82--2)

Fig. 1

Fig. 2

Fig. 3

I claim:

The ornamental design for a confection, substantially as shown.
